CLAIM

The ornamental design for an end standard for a lounge seat, substantially as shown.

DESCRIPTION

FIG. 1 is a view in side elevation of an end standard for a lounge seat, showing my new design,
FIG. 2 is a plan view thereof,
FIG. 3 is a bottom view thereof,
FIG. 4 is a rear view thereof,
FIG. 5 is a front view thereof; and
FIG. 6 is a sectional view taken on line 6—6 in FIG. 1 thereof.

FIG. 2

FIG. 1

FIG. 3

FIG. 4

FIG. 5

FIG. 6
